UNITED STATES PATENT OFFICE

121,423

DESIGN FOR A COMBINATION BED LAMP AND RADIO

Bernard A. Mitchell, Chicago, Ill.

Application March 29, 1940, Serial No. 91,335

Term of patent 7 years

To all whom it may concern:

Be it known that I, Bernard A. Mitchell, a citizen of the United States, residing at Chicago, in the county of Cook and State of Illinois, have invented a new, original, and ornamental Design for a Combination Bed Lamp and Radio, of which the following is a specification, reference being had to the accompanying drawing, forming part thereof.

The drawing is a perspective view of a combination bed lamp and radio showing my new design. The side not shown is similar to the side shown in the drawing. The top section is substantially plain.

I claim:

The ornamental design for a combination bed lamp and radio, as shown and described.

BERNARD A. MITCHELL.
